CLAIM

The ornamental design for a watch case, as shown and described.

DESCRIPTION

FIG. 1 is a front elevational view of a watch case showing my new design;

FIG. 2 is a back elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front, right side perspective view thereof; and, FIG. 8 is a back, left side perspective view thereof.

The broken lines in the drawing figures depict unclaimed subject matter that forms no part of the claimed design.

1 Claim, 8 Drawing Sheets
